UNITED STATES PATENT OFFICE

2,366,019

PLOTTING INSTRUMENT

Charles Fremont Golden, Denver, Ind.

Application January 25, 1943, Serial No. 473,520

1 Claim. (Cl. 33—75)

This invention relates to a plotting instrument and it is more especially an improvement upon the structures shown in my patents, 1,869,358 and 2,104,515.

An object of the invention is to provide a simple and compact instrument designed for use in plotting by bearings, azimuth and traverse, the several parts of the instrument being combined in such a manner as to permit continuous plotting accurately, conveniently and speedily.

Another object is to provide an instrument of this character which can be used in practically all fields where drafting and designing of equipment is necessary.

A still further object is to provide two protractors so graduated as to make it possible to cover the complete circle in azimuth layouts, it being possible to use the instrument as a T-square, a compass, at least five scales, a parallel, and vernier.

Another object is to provide an instrument the edges of which are so formed that it can be used in inking without danger of smearing.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

In the accompanying drawing the preferred form of the invention has been shown.

In said drawing

Figure 1 is a plan view of the instrument, the extension arm being shown by broken lines in folded position.

Figure 2 is a section on line 2—2, Figure 1, said section showing a portion broken away.

Figure 3 is a section on line 3—3, Figure 2.

Figure 4 is a section on line 4—4, Figure 2.

Figure 5 is a section on line 5—5, Figure 2.

Figure 6 is a bottom plan view of one end portion of the instrument, a portion of the extension arm being shown folded, the extended position of said arm being shown by broken lines.

Figure 7 is a bottom plan view of the free end portion of the extension arm and its guard or keeper.

Figure 8 is a section on line 8—8, Figure 7.

Figure 9 is a view similar to Figure 4 but showing a modified construction.

Referring to the figures by characters of reference, 1 designates the elongated flat blade of 55

the instrument which, as shown in Figs. 4 and 5, has the bottom portions of its side edges beveled as at 2 so that, while the instrument is being used for inking, there is no danger of smearing the work. The edges of the blade are straight and one of these straight edges, 3, is extended to the center of the straight side 4 of a semi-circular head or protractor 5 which is integral with the blade. The graduations 5a on the outer edge of the protractor are extended through 180° and, for the purpose of providing other scales in this part of the instrument, an arcuate slot 6 extending through 180° is provided, this slot being interrupted at its center by spaced connecting webs 7. Thus three arcuate edges within a range of 180° are provided along which any desired graduations can be located. For example one of the protractors can be graduated in mills and the other in degrees and thirty minute readings, the degree markings being specially arranged so as to make it possible to cover the complete circle in azimuth layouts. In order to permit the extension of the slot 6 through 180° degrees, the straight edge 4 is offset at its ends as shown at 8. Located at the point where the straight edges 4 and 3 meet, there is a centering pin 9 carried by a bracket 10 on the head 5, this pin being shiftable longitudinally as desired. It can be of a construction already well known. A longitudinal slot 11 is provided in the blade 1. The slot is parallel with the edge 3 and also with the opposed edge 12 of the blade. One end of the slot is in line with the edge 4 while the other end terminates adjacent to the free end 35 of the blade. That portion of the blade between edge 3 and slot 11 is of greater thickness than that part of the blade between slot 11 and edge 12, the thicker portion of the blade extending longitudinally thereof being indicated at 13. An extension blade 14 having parallel straight edges is adapted to extend longitudinally of the blade along the bottom surface of the thin portion thereof and this extension has an ear 15 at one end extending at right angles therefrom and 40 pivotally joined to the blade 1 as shown at 16. This pivot is located adjacent the slot 11 and to the free end of the blade. Adjacent to the other end of the blade there is a keeper in the form of a diagonally disposed undercut shoulder 17 and the free end of the blade is beveled, as at 18 so as to wedge into engagement with the shoulder as shown in Fig. 7 with the outer straight edge of the blade close to and parallel with the edge 12. The parts 15 and 13 are so located that when 45 blade 14 is swung outwardly about pivot 16 it will

be brought into position with its outer edge in line with the edge 3 and when it is thus located the extension 15 will come against a stop shoulder 19 formed by one end of the thickened portion 13 so that the straight edge of the extension will thus constitute an accurate continuation of the straight edge 3. This is indicated by broken lines in Fig. 6.

An ear 20 is fixedly joined to the head 5 and has pivoted to it a sight 21 in which is a small opening 22. Another sight in the form of a pin 23 is pivotally connected to the blade 1 as shown at 24 and the two sights are so located that when they are in use, they will be on a line parallel with the edge 3. When not in use the sights are adapted to be folded downwardly against the instrument as shown in Fig. 1. In Figs. 3 and 5 the two sights have been shown raised into position for use.

A slide 25 is extended transversely of the blade and is provided with a projecting eye 26 the center of which is adapted to register with the edge 3 as shown. A screw 27 is slidable in the slot 11 and has a clamping head 28 adapted to frictionally engage the bottom surface of the blade 1. This screw carries a nut 29 which, when loosened, permits the slide to be shifted longitudinally of the blade so as to be brought to any selected graduation thereon. When the nut 29 is tightened the slide will be held against movement.

It will be noted that the inner protractor provided by the edges 30 of slot 6 is provided with graduations designed for azimuth and degree layouts. The blade 1, in the structure illustrated, has five sets of longitudinally extended series of graduations. The graduations along the edge 3 are for indicating $\frac{1}{20,000}$ yd. The graduations along edge 31 are graduated in $\frac{1}{62,500}$ yd. The edge 32 of slot 11 is graduated in $\frac{1}{2}$ inch. An intermediate line extending longitudinally of the blade between the edges 32 and 12 and indicated at 33 is graduated in $\frac{1}{15,840}$ yd., while the edge 12 is graduated in $\frac{1}{48,000}$ yd. The graduations along the edge of the extension blade 14 constitute continuations of those along the edge 3 of blade 1.

The graduations along the straight edge 4 indicate $\frac{1}{20}$ yd.

In cases where an extension arm is not necessary the slide can be made as shown at 34 in Fig. 9 wherein the side edges are inturned as at 35 for the purpose of straddling the adjacent edges of the blade. In other respects this construction can be the same as that shown in the other figures.

All scales used on this instrument are standard scales and heretofore, in order to obtain these measurements, it has been necessary to make the blade 1 detachable and to have substitute blades to be used in lieu thereof, the blades being provided with different graduations respectively. Obviously with this multiple arrangement of graduations, the use of separate blades is dispensed with and all of the measurements can be obtained with the one instrument.

The edges 4, 3 and 12 can be used for the purpose of laying out right angles, as will be obvious.

What is claimed is:

A plotting instrument including a head, a blade extending from the head and having a longitudinal slot, an extension blade hingedly mounted on one face of the blade and pivotally connected to said blade and adjacent to that end thereof remote from the head, said blade being movable into position under the blade and parallel with and into position between the slot and one longitudinal edge and being movable to position outwardly from the blade with one edge in line with one of the edges of the blade, said blade having an obliquely disposed transverse shoulder on one face provided with a tapered groove, the free end of the extension blade being tapered and obliquely disposed for wedging engagement in the groove to hold the blade frictionally in folded position between edges of the slotted blade, and cooperating means on the two blades for limiting the movement of the extension blade when swung outwardly about its pivotal connection.
